CLAIM

The ornamental design for an electronic keyboard instrument as shown and described.

DESCRIPTION

FIG. 1 is a perspective view of an electronic keyboard instrument showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the portion taken at line-8 in FIG. 1;

FIG. 9 is an enlarged view of the portion taken at line-9 in FIG. 2;

FIG. 10 is an enlarged view of the portion taken at line-10 in FIG. 3;

FIG. 11 is a cross-sectional view taken along line 11-11 in FIG. 2; and,

FIG. 12 is an enlarged cross-sectional view of the indicated portion shown in rectangle 9 taken along line 12-12 in FIG. 2, with the internal mechanism omitted.

The dashed broken lines illustrate portions of the electronic keyboard instrument that form no part of the claimed design. The dot-dash broken lines define the bounds of the claimed design and form no part thereof. The dot-dot-dash broken lines represent boundaries of the enlarged portion and form no part of the claimed design.
